US00D855729S

(12) **United States Design Patent** (10) Patent No.: **US D855,729 S**
Kim (45) Date of Patent: ** Aug. 6, 2019

(54) **SMART STUN GUN FOR SELF DEFENSE**

(71) Applicant: **INFOS TECHNOLOGY CO., LTD.**,
Seoul (KR)

(72) Inventor: **Beom Jin Kim**, Seoul (KR)

(**) Term: **15 Years**

(21) Appl. No.: **35/504,934**

(22) Filed: **Nov. 13, 2017**

(80) **Hague Agreement Data**

Int. Filing Date: **Nov. 13, 2017**

Int. Reg. No.: **DM/098647**

Int. Reg. Date: **Nov. 13, 2017**

Int. Reg. Pub. Date: **May 18, 2018**

(51) **LOC (12) Cl.** 22-01

(52) **U.S. Cl.**

USPC **D22/104**

(58) **Field of Classification Search**

USPC D22/101, 104, 117; D26/38

CPC F41B 11/55; F41B 11/51; F41B 11/62

See application file for complete search history.
